UNITED STATES PATENT OFFICE.

CHARLES I. E. MASTIN, OF MIDLAND PARK, NEW JERSEY, ASSIGNOR TO STEWART DICKSON, OF NEW YORK, N. Y.

PACKING.

1,208,605.

Specification of Letters Patent.

Patented Dec. 12, 1916.

Application filed September 2, 1916. Serial No. 118,236.

To all whom it may concern:

Be it known that I, CHARLES I. E. MASTIN, a citizen of the United States, residing at Midland Park, in the county of Bergen and State of New Jersey, have invented certain new and useful Improvements in Packings; and I do hereby declare the following to be a full, clear, and exact description of the invention, such as will enable others skilled in the art to which it appertains to make and use the same.

This invention relates to packings, and has for an object to provide a packing embodying new and improved features of strength, elasticity and wearing qualities.

A further object of the invention is to provide a packing having a metal reinforce vulcanized into the structure composed of vulcanized rolls upon opposite sides of the reinforce, each provided with a live rubber core.

With these and other objects in view the invention consists in certain novel features of construction, combination and arrangement of parts as will be hereinafter more fully described and claimed.

In the drawings:—Figure 1 is a view of the packing in side elevation, the parts being broken away to show the built-up structure. Fig. 2 is a transverse sectional view taken on line 2—2 of Fig. 1. Fig. 3 is a perspective view of the metal reinforce. Fig. 4 is an enlarged transverse sectional view through one of the rolls.

Like characters of reference designate corresponding parts throughout the several views.

The improved packing which forms the subject-matter of this application comprises a metal reinforce 10 formed in the general construction of an I-beam, having cut-out portions 11 which permit the reinforce to be

curved to correspond to the required curvature of the packing as shown particularly at Fig. 1. Two rolls of material are made as 45 shown in the enlarged view at Fig. 4, comprising each a live rubber core 12 with rubberized fabric rolled around such core in the usual well-known manner for vulcanizing purposes. The two rolls are placed 50 upon opposite sides of the reinforce 10 intermediate its two flanges. A plurality of strips of rubberized fabric 13 and 14 are now placed on the outer periphery of the associated rolls and reinforce, and a final 55 outer fabric 15 placed upon the periphery of the two fabrics 13 and 14 and brought down along the sides of the rolls. The entire structure is now by some approved means pressed and molded into the form shown at 60 Fig. 2, in cross section substantially rectangular, with the inner periphery of the metal reinforce flush with the inner surface of the completed packing. The entire structure is now vulcanized in the usual well-known 65 manner, and the packing is complete.

I claim:—

1. In a packing, a metal reinforce, rolls located upon opposite sides of the reinforce, and each comprising a rubber core and 70 fabric laminations, and fabrics spanning over and joining the rolls together.

2. A packing comprising a metal reinforce of substantially I-beam form having cut-out portions upon one side forming the inner 75 surface of the packing, rolls located upon opposite sides of the metal reinforce composed of rubber cores and laminations of rubberized fabric, rubberized fabrics spanning the cores, and the entire structure vul- 80 canized connecting the rolls through the cut-out portions of the metal reinforce.

In testimony whereof I affix my signature.

CHARLES I. E. MASTIN.
